UNITED STATES PATENT OFFICE.

FRANCIS L. POMMER, OF RICHMOND COUNTY, NEW YORK.

DESIGN FOR MATCH-SAFE.

Specification forming part of Design No. **11,427**, dated September 23, 1879; application filed August 11, 1879.
[Term of patent 3½ years.]

To all whom it may concern:

Be it known that I, FRANCIS L. POMMER, of the county of Richmond, in the State of New York, have originated and produced a Design for a Match-Safe, of which the following is a full, clear, and exact description, reference being had to the accompanying photographic illustration, making part of this specification.

The design is shown substantially in the said accompanying illustration.

The body of the safe, A, is in the form of a cylinder, and made to present the appearance of a champagne-cork, while the end or top B is in the form of a disk, and made to present the appearance of silver. A brand or trademark is applied, if preferred, upon the top.

The effect of the employment of the silver

disk or top in the relation described and shown is highly artistic and in a marked degree striking and original.

While I believe a match-safe has never heretofore been made in the form of a cork, I do not claim, broadly, such a design; but

What I claim is—

A design for a match-safe, consisting of the body A, made to resemble a champagne-cork, and the silver end B, substantially as shown and described.

Witness my hand this 9th day of August, A. D. 1879.

F. L. POMMER.
